UNITED STATES PATENT OFFICE.

LEON BENOIT AND PERCIVAL FAULKNER KING, OF VANCOUVER, BRITISH COLUMBIA,
CANADA.

WRENCH.

1,347,491.

Specification of Letters Patent.

Patented July 27, 1920.

Application filed February 15, 1919. Serial No. 277,330.

To all whom it may concern:

Be it known that we, LEON BENOIT and PERCIVAL FAULKNER KING, both subjects of the King of Great Britain, and both residents of the city of Vancouver, in the Province of British Columbia, Canada, have invented certain new and useful Improvements in Wrenches, of which the following is a specification.

10 Our invention relates to improvements in wrenches, and the object of our invention is to devise a wrench capable of being operated with one hand with great facility, which is possessed of great strength while 15 being of light construction, and which is simple and cheap to manufacture.

We attain this object by the construction illustrated in the accompanying drawings in which—

20 Figure 1 is a side elevation of the wrench. Fig. 2 is a fragmentary view showing the locking arrangement.

Fig. 3 is a detail view of the lock member.

25 Fig. 4 is a cross section taken on the line 5—5 of Fig. 1.

Similar figures of reference indicate similar parts throughout the several views.

The wrench consists of a shank 1 having 30 its upper end turned over at right angles to form a rigid jaw member 2 and its lower end broadened as at 3 and provided with apertures 4 and 5, the aperture 4 being of a size to enable the index finger to be inserted 35 therein and the aperture 5 being of such length to allow two or all the remaining fingers to be passed through it, and in order to allow of the maximum gripping pressure to be exerted with ease and convenience the 40 portion 3 is preferably bent over approximately on the line indicated by the numeral 6 and as shown in Fig. 4. Mounted on the forward edge of shank 1 for vertical movement thereon is a shank 7 the upper end of

45 which forms the sliding jaw and the upper edge 8 of which is inclined, as shown in Fig. 1, so that the mouth of the jaw space 9 is wider than the back. The inner end of the edge 8 is rounded as at 10 so that it may 50 roll, as it were, on the edge of shank 1 when opening and the shank 7 is connected to shank 1 by straps 11 and 12 the upper one of which is substantially U-shaped in formation, the legs of the straps being rigidly

secured to the shank 7. The upper strap 11 55 is so arranged that the upper edge of the transverse portion 13 of the U bears, when the wrench is closed, on the rear edge of the shank 1, the point of contact being indicated in Fig. 1 by the letter A, its lower 60 edge however being spaced from the edge of the shank 1, to permit sufficient play to open the wrench, and the point of contact A is in advance of the point of rolling contact between the two shanks 1 and 7, this latter point being indicated by the letter B. The lower strap 12 is formed of two plates connected by a bar 26 and is extended sufficiently to allow of the mounting therebetween of a locking member 14 70 capable of swinging around a stationary square pin 15 to either a horizontal or vertical position, the length of the member 14 being such that when swung to a horizontal position its inner end 16 will bear on 75 the rear edge of the shank 1 and thus prevent disengagement of the locking teeth 17 and 18 with which the respective shanks 1 and 7 are provided, as shown in Fig. 1. The bar 26 forms a stop for the 80 member 14 when vertical.

The member 14 is recessed on one side, as at 19, and in the recess is mounted a spring 20 divided at its ends as at 21 and 22, these ends being under tension and operative on 85 the square sides of the pin 15 to maintain the member 14 in either the horizontal or vertical positions when swung thereto. The lower end of the shank 7 is provided with a wide portion 23 provided with an aperture 90 24 through which the thumb may be inserted and in order that the most efficient grip may be provided for the thumb when in the act of operating the shank 7, the outer edge of the portion 23 is turned 95 upwardly, as indicated at 25 in Figs. 1 and 4.

The operation of the wrench will be apparent, as it will be seen that, referring to Fig. 1, on inserting the thumb in aperture 100 24, the index finger in aperture 4, and the other fingers in aperture 5, the lower ends of the shanks 1 and 7 may be spread apart to disengage the teeth 18 from teeth 17 so that the shank 7 may be slid up or down on shank 1 by the thumb to adjust the jaw space 9 to enable the wrench to be placed on the nut to be operated on, after which the

shanks may be brought together by the closing of the hand to reengage the teeth 17 and 18 so that the nut may be turned either to tighten or slacken it.

5 The action of the wrench is substantially a scissor-like action, being opened by the spreading of the thumb and fingers and closed by the closing of the hand, so that it is simple to operate and, having minimum 10 of parts is cheap to manufacture, while being strong and highly efficient.

What we claim as our invention is:

1. A wrench comprising a toothed shank having a rigid jaw, a second shank mounted 15 on the edge of the first-mentioned one provided with teeth adapted to coöperate with the teeth of the same to lock it against retraction and having its upper end adapted to form the sliding jaw for the wrench, the 20 lower ends of said shanks being formed as gripping handles and provided respectively with thumb and finger apertures whereby the shanks may be spread by the act of opening the hand and closed by the act of closing 25 it.

2. A wrench comprising a toothed shank having a rigid jaw at its upper end and its lower end provided with an aperture for the index finger and one for the two or all 30 remaining fingers, a second shank mounted on the edge of the first-mentioned one provided with teeth adapted to coöperate with the teeth of the same to lock it against retraction having its upper end adapted to 35 form the wrench sliding jaw and its lower end provided with a thumb aperture, and means for slidably connecting the second-mentioned shank to the first-mentioned one.

3. A wrench comprising a toothed shank 40 having a rigid jaw at its upper end and its lower end formed as a broad portion offset from the main shank and provided with an aperture for the index finger and one for the two or all remaining fingers, a second 45 shank mounted on the edge of the first-mentioned one provided with teeth adapted to coöperate with the teeth of the same to lock it against retraction having its upper end adapted to form the wrench sliding jaw and its lower end broadened and provided 50 in the broad portion with a thumb aperture, the outer edge of the broad portion being turned reversely to the offset portion aforesaid, and means for slidably connecting the 55 second-mentioned shank to the first-mentioned one.

4. A wrench comprising a shank having a rigid jaw, a second shank mounted on the edge of the first-mentioned one having its 60 upper end adapted to form the sliding jaw for the wrench and rounded at one corner for rolling contact with said first shank, and an inclined strap secured to the second shank embracing the first one and bearing at its 65 upper embracing edge on the rear edge of

the first shank at a point in advance of the point of rolling contact of the second shank with the first one.

5. A wrench comprising a toothed shank having a rigid jaw at its upper end and its 70 lower end provided with an aperture for the index finger and one for the two or all remaining fingers, a second shank mounted on the forward edge of the first-mentioned one provided with teeth adapted to coöperate 75 with the teeth of the same to lock it against retraction having its upper end edge inclined downwardly and outwardly and adapted to form the wrench sliding jaw and its lower end provided with a thumb aperture, the upper end of said second shank being rounded at one corner for rolling contact with the first-mentioned shank, and a strap secured to the second-mentioned shank adjacent its upper end embracing the first- 80 mentioned one and bearing at its upper embracing edge on the rear edge of the same at a point in advance of the point of rolling contact of the second shank and the first one, its lower embracing edge being spaced from 85 the edge of the first-mentioned shank to provide a gap therebetween.

6. A wrench comprising a toothed shank having a rigid jaw at its upper end and its lower end provided with an aperture for the 90 index finger and one for the two or all remaining fingers, a second shank mounted on the forward edge of the first-mentioned one provided with teeth adapted to coöperate 95 with the teeth of the same to lock it against retraction, having its upper end edge inclined downwardly and outwardly and adapted to form the wrench sliding jaw and its lower end provided with a thumb aperture, the said upper end of the second shank 100 having one of its corners rounded for rolling contact with the first shank, and a strap secured to the second-mentioned shank adjacent its upper end embracing the first-mentioned one and bearing at its upper embracing edge on the rear edge of the same at a point in advance of the point of rolling contact of the second shank and the first one, its lower embracing edge being spaced from 105 the edge of the first-mentioned shank to provide a gap therebetween, a strap secured to the second shank intermediate its length also embracing the first one, and a supplemental locking device mounted on said strap adapted to lock said shanks against lateral spreading movement.

7. A wrench comprising a toothed shank having a rigid jaw at its upper end and its lower end provided with an aperture for the index finger and one for the two or all remaining fingers, a second shank mounted on the forward edge of the first-mentioned one provided with teeth adapted to coöperate 125 with the teeth of the same to lock it against retraction having its upper end edge in- 130

clined downwardly and outwardly and adapted to form the wrench sliding jaw and its lower end provided with a thumb aperture, the upper end of said second shank being rounded at one corner for rolling contact with the first-mentioned shank, a strap secured to the second-mentioned shank adjacent its upper end embracing the first-mentioned one and bearing at its upper edge 10 on the rear edge of the same at a point in advance of the point of rolling contact of the second shank and the first one, its lower embracing edge being spaced from the edge of the first-mentioned shank to provide a gap therebetween, a strap secured to the second shank intermediate its length also embracing the first one, and a pawl mounted 15 on said strap normally clear of the rear edge of the first-mentioned shank adapted to 20 be swung to bear against the same.

8. A wrench comprising a toothed shank having a rigid jaw at one end, a second

shank mounted to slide on one edge of said first shank provided with teeth interlocking with said first-mentioned teeth to prevent relative sliding movement of the two shanks, a strap secured to the second-mentioned shank adjacent its upper end, embracing the first-mentioned one, a second strap secured to the second shank intermediate its length also embracing the first one, a pivot pin carried by said second strap, a lever mounted to swing on said pin provided with a cam face for engagement with said first shank to prevent spreading 25 of the shanks, and having a recess in one side, a spring seated in said recess and engaging said pivot pin to normally hold the lever inoperative.

Dated at Vancouver, B. C., this 16th day 40 of January, 1919.

LEON BENOIT.
PERCIVAL FAULKNER KING.
